MEDICAL INSTRUMENT PANEL

Harvey F. Glassner, Los Angeles, Lee R. Baessler, Manhattan Beach, and Lech Pisarski, Los Angeles, Calif., assignors to Humetrics Corporation, Los Angeles, Calif., a corporation of Delaware

Filed Oct. 14, 1969, Ser. No. 19,560

Term of patent 14 years

Int. Cl. D24—02

U.S. Cl. D83—1

FIG. 1 is a perspective view of an instrument panel illustrating our new design.

The broken lines are shown for illustrative purposes only and form no part of the claim.

We claim:

The ornamental design for a medical instrument panel, substantially as shown and described.
